JULIAN DEMATTEIS, OF BATAVIA, IOWA.

FLOOR SCRUBBING AND POLISHING MACHINE.

1,046,742.

Specification of Letters Patent. Patented Dec. 10, 1912.

Application filed February 10, 1912. Serial No. 676,809.

To all whom it may concern:

Be it known that I, JULIAN DEMATTEIS, residing at Batavia, in the county of Jefferson and State of Iowa, have invented a new and Improved Floor Scrubbing and Polishing Machine, of which the following is a specification.

This invention relates to improvements in that class of floor scrubbing machines in the construction of which is included a fluid holding chamber and valve controlled means for feeding the fluid to the scrubbing and polishing elements as desired.

My present invention seeks to provide an improved scrubbing and polishing means of the general character stated, in which the parts are especially so designed and co-operatively arranged whereby the manufacture thereof is economically effected, and the said parts compactly and simply arranged so the use of the machine is easily understood and convenient for the operator.

With other objects in view, that will hereinafter appear, my present invention in its generic nature, embodies an improved arrangement of the brushing and polishing rollers and means controlled by certain manipulations of the handle or pushing lever of the machine, for providing a substantially continuous reuse of the scrubbing fluid and under a minimum waste thereof.

In its more complete nature, my present invention includes an improved means for adjusting the floor pressure of the scrubbing and polishing rollers, means operable by certain manipulations of the pushing lever or handle of the machine for effecting a rise of the said polishing and scrubbing rollers to provide for the maximum spread of the water when let out of the fluid chamber to the said rollers.

In its more subordinate features my present invention consists of the peculiar and novel combinations and arrangement of the parts hereinafter fully explained, specifically pointed out in the appended claims and illustrated in the accompanying drawings, in which:

Figure 1 is a perspective view of my floor scrubbing and polishing machine. Fig. 2 is a vertical longitudinal section thereof, taken on the line 2-2 on Fig. 4, the parts being in the operative position, the fluid feed from the main chamber or reservoir being closed. Fig. 3 is an end elevation of my invention, the outer casing or cover plate and one of

the carrier wheels being omitted. Fig. 4 is a top plan view of the machine, part of the top being broken away, and the mechanism at one end shown in horizontal section, to more clearly illustrate the same. Figs. 5 and 6 are perspective detail views of parts hereinafter referred to. Fig. 7 is a transverse section of the machine taken on the line 7-7 on Fig. 2. Fig. 8 is a plan view, parts being in horizontal section of the dirty water receptacles, and parts of the controlling devices that actuate the closure valves for the outlets of the said receptacles. Fig. 9 is a detail section on the line 9-9 on Fig. 8. Fig. 10 is a detail perspective view of one of the swinging levers of the aforesaid controlling devices. Figs. 11 and 12 are detail longitudinal sections of one of the journal ends of the scrubbing and polishing rollers respectively. Fig. 13 is a detailed side elevation of a slightly modified construction of the means for raising the rollers from the floor during the operation of discharging the scrubbing fluid onto the floor. Fig. 14, a detail section thereof on the line 14-14 on Fig. 13, and Fig. 15 is a detail view of the lifting lever device hereinafter specifically referred to.

In carrying out my present invention, the main or body portion of the machine is preferably made of stiff sheet metal, of the general shape shown in Figs. 1 and 2 of the drawings, and the said body comprises an outer casing or shell consisting of the sides ⁹⁰ *a*, rounded ends *b*, and a top *c*, the latter having a central opening *d* that receives a filling tube 3, presently again referred to.

2 designates rubber tired carrier wheels of which there are two at each side, and they are mounted upon steel stub shafts 50 riveted or otherwise made fast to the plates 21, secured upon the side of the casing. The carrier wheels 2 at one or both sides of the machine, each have an internal gear 43, that meshes with and imparts motion to each of the pinions 28 fixedly held on the stub ends 45 that form parts of the hollow steel shafts 44, on which the hubs 29 of the polishing roller and the scrubbing cylinder are mounted, as best shown in Figs. 11 and 12 of the drawings. At each end of the casing is located a pocket or pan 42, and these alternately catch the dirty water from the rollers as the same is carried up by the similarly moving rollers 24-25.

12 designates a horizontal division plate

that forms the bottom of the main reservoir tank 1, and the said bottom 12 has a central slot 12^a that extends transversely its full width, and in which is fixedly held a bar 7 provided with a series of outlets 7^a and a central elongated slot 7^b, the purpose of which will presently appear. Bar 7 has a slide way 7^c on its under side extending its length and in this slideway is mounted a slide valve 40 having a series of holes 40^a, adapted to be moved into and out of register with the discharging outlets 7^a in the bar 7. 5

35 designates a bifurcated head block made fast to the side valve 40, the shank 35^a of 10 which passes through the said slide valve 40 and has movement in the elongated slot 7^b in the bar 7, see Fig. 7. Shank 35^a has a stop collar 35^b, which extends below the slide valve 40 and carries a screw nut 38, presently again referred to.

For shifting the slide valve 40 to either open or close, the discharging apertures in the bar 7, either of the two ways shown in the drawings may be used but, I prefer to 25 construct each machine with the two means shown since it provides for conveniently controlling the shifting of the slide valve 40 by either the hand or foot action of the operator.

30 Referring now more particularly to Figs. 2 and 7 of the drawings, 34 designates a bell crank lever, the shifting of which not alone actuates the slide valve 7, but also the valves that control the discharges from the dirty 35 water pockets, hereinafter fully explained. Lever 34, is pivotally mounted in a bracket 53 on the inside of the filling tube, and it has its long or pendent member 34^a pivotally connected to the head block 35. The other 40 member of the lever 34 has a pair of laterally projected lugs 34^c—34^c, and a third laterally projected lug 34^d, the latter engaging a stout leaf spring 37 mounted in the filling tube, and which normally swings the lever 34 to 45 shift the valve 40 to close off the discharges from the main tank.

In the drawings two ways are shown for depressing the bell crank lever 34 to shift valve 40 to open the discharges from the 50 tank, both of which engage with the upper one of the lateral lugs 34^c. One of the lever depressing devices, consists of an eccentric cam 33 rotatable with a shaft 17 mounted in bearings 17^a, of a yoke holding frame 10, preferably cast integral or otherwise made solid with the feeding tube 3, as is clearly shown in Fig. 7.

11 designates a yoke frame, the ends 11^a— 55 11^b of which engage the squared ends of the shaft 17, and are clamped thereon by the nuts 18.

14 designates a wooden handle that fits a socket 11^b in the yoke 11 as shown.

By reason of arranging the yoke and handle and providing the shaft with the eccen-

tric cam as shown and described, the operator by swinging the handle over, in the direction indicated by the arrow "x", see Fig. 1 to the dotted position, Fig. 2, the cam 33 swings the bell crank lever against the tension of the spring 37, and thereby shifts the valve 40 to the opening position, to allow for a clean water discharge between the polishing and scrubbing rollers, it being obvious that as the handle is swung back again, the spring 37 shifts the lever 34 to close the valve 40. 70

54 designates a pusher or guide bolt mounted in the lateral lugs of the lever 34, and it carries an adjustable head 32 that normally projects in a plane above the top of the feed tube 3. 80

3^a designates a cover plate for the port 3 that is hinged to swing in the horizontal plane. Cover 3^a has a convexed seat 30 to fit over the pin head 32 when the said cover is closed. Head 32 is rounded so that the cover 3^a in closing, depresses the pin and shifts the lever 34 to open the valve 40. By providing the cover 3^a, the same can be easily shifted to the open or closed position by the foot of the operator, engaging with the cover extension 30^a. 85

Referring now to the pockets for holding the dirty water, it should be here stated, that in my machine I provide for the reuse of the dirty water with each fresh supply of clean water, providing, as it were, a fountain action, since the reuse of the dirty water is kept up until all of the clean water is out of the main reservoir, after which the machine is conveyed to a suitable point for emptying the dirty water and for refilling with clean water. 95

Each of the pockets 42 has a nose portion 105 42^a that extends closely to the rollers so as to alternately catch and in a measure scrape off the water carried up and over by the rollers, see full arrows *y* and dotted arrows *z* on Fig. 2, and each of the said pockets has its bottom portion formed with a discharging slot 42^b, normally closed by a swinging gate valve 31, which is fixedly secured to the lower end of a vertically extended rock shaft 30^x, provided with a crank 39. 110

For operating the crank shafts 30^x for both pockets 42 simultaneously, I connect them by means of double link arms or levers 5, arranged as diagrammatically shown in Fig. 8, and as shown in detail in Figs. 2 and 7,—which show the inner slotted ends 50 of the levers 5 as receiving the lower extension of the shank of the sliding block 35, and in such a manner that when the bell crank lever 34 is shifted to open the slide valve 40, the levers 5 and the valves 31 are swung to the dot and dash positions shown in Fig. 8. 115

To provide for conveniently adjusting the pressure of the scrubbing and the polishing rollers 24—25, their stub shaft portions 45 120 130

move in the cut out portions $p-p$ of the sides of the casing, see Fig. 3, and are journaled on the pendent arms 60 of bell crank levers 6 fulcrumed on the stub axles on 5 which the carrier wheels are journaled.

The long arms 61 of each set of levers 6 extend toward each other and terminate in slotted heads 62 that lap and receive the shank 47^a of a nut 47, that receives the 10 threaded shank 27, of an adjusting member, the lower end of which has a stepped bearing in the lug 48 on the casing, and whose upper end extends through and above the yoke frame member 10, and terminates in a milled 15 head 9. A coiled spring 26 is mounted on the shank 27 and normally holds the rollers 25, 24 against the floor, it being understood that by adjusting the screw shanks 27, the nuts 47 will travel up or down and regulate 20 the degree of pressure of the said rollers 24 and 25.

In Figs. 13, 14 and 15, I have shown a somewhat modified construction of the rollers adjusting means, and in this form in addition to the adjusting devices shown in Figs. 3 and 7, means are included for bodily raising the rollers off the floor irrespective 25 of their degree of pressure adjustments, whenever the water is discharged from the reservoir and the end pockets, so as to give the said water free flow over that part of the floor being worked. For such purpose a lifter device is used with each adjusting shank, as shown in detail in Fig. 15, the 30 same consisting of an apertured body 91 rockably mounted in a bracket 10^c on the plate 10, a toe portion 92 slotted for fitting on the shank under the head 9 and a heel 93 that projects in the path of an eccentric cam 35 94, on the handle yoke member 11, which engages and depresses the heel 93, when the handle is swung forwardly to open the slide valve 40 and valves 31, and thereby lift the shanks 27 against the tension of the springs 40 26, and in consequence swing the crank levers 6 to raise the rollers 24—25 off the floor.

From the foregoing description taken in connection with the drawings, the complete 50 construction, the manner in which the machine is operated, and its advantages are believed to be sufficiently apparent to avoid necessity of further description thereof.

Having thus described my invention, what 55 I claim is:—

1. In a floor scrubbing machine, a clean water tank, a scrubbing roller, a pocket arranged to receive the dirty water carried over by the roller, valve controlled outlets 60 for the tank and pocket, and means manually operable externally of the machine for simultaneously shifting the valves for the said outlets to the open position, and other means for closing the said valves.

65 2. In a scrubbing machine of the charac-

ter stated, a scrubber, a clean water receptacle, a receptacle for collecting the water taken up by the scrubber, and means for effecting the simultaneous discharge of the clean and dirty water to the scrubber, the 70 said means including valved outlets, a pivoted handle and connections that join the handle and the valved outlets operable as the handle is swung down to open the said valved outlets.

3. In a scrubbing machine of the character described, in combination with a scrubbing roller, a water supply tank having valve controlled outlets; of a means for simultaneously opening up the water feed. 75 80 and elevating the scrubbing roller.

4. In a scrubbing machine of the character stated, and including a pivoted yoke handle frame; the combination with a water supply tank having a valve controlled outlet, a dirty water receptacle, a rotary scrubber that carries the dirty water to the receptacle, an adjustable support for the scrubber, including means for holding the scrubber under pressure, and other means 85 90 for bodily elevating the adjusting means with the scrubber.

5. In a scrubbing machine of the character stated, and including a pivoted yoke handle frame; the combination with a water supply tank having a valve controlled outlet, a dirty water receptacle, a rotary scrubber that carries the dirty water to the receptacle, an adjustable support for the scrubber, including means for holding the scrubber under pressure, and other means for elevating the adjusting and the pressure devices with the scrubber. 95

6. In a scrubbing machine, a scrubber, an adjustable support for the said scrubber, means for holding the scrubber under pressure, other means for elevating the scrubber and its adjusting devices, the said other means including a bell crank support for the scrubber in connection with the adjusting devices, and a pivoted handle frame including a cam for engaging and rocking the bell crank support to elevate the scrubber. 100

7. In a floor scrubbing machine of the character stated, and including a swingable yoke handle and scrubbing rollers, a bell crank support for each of the scrubbing rollers pivotally mounted upon the machine casing, and pressure springs for holding the said scrubbing rollers on the floor, an adjusting device for each set of bell cranks at each side of the casing, and means for simultaneously bodily lifting the said rollers, adjusting and pressure devices at each side whereby to lift the said rollers, said means being operable by the swinging of the yoke handle. 115

8. In a floor scrubbing machine of the character stated, and including a swingable yoke handle and scrubbing rollers, a bell 120 125

crank support for each of the scrubbing rollers pivotally mounted upon the machine casing, and pressure springs for holding the said rollers on the floor, an adjusting device 5 for each set of bell cranks at each side of the casing, said adjusting devices including a headed screw shank, a screw nut engaging the shank and the bell cranks, and means for simultaneously bodily lifting the 25 scrubbing rollers adjusting and pressure devices at each side of the casing to lift the scrubbing rollers, the said means including a rocking member that engages the underside of the head of the screw shank and has 30 a heel portion, and a cam device on the yoke handle frame that engages the said heel portion when the handle is swung forward, and thereby lift the headed screw shank and its screw nut that engages the bell cranks.

9. In a floor scrubbing machine of the 15 character stated, and including a yoke handle and scrubbing rollers, a bell crank support for each of the scrubbing rollers pivotally mounted upon the casing, and spring pressed to hold the said rollers against the 20 floor, an adjusting device for each set of

JULIAN DEMATTEIS.
